SUGAR SIFTING AND DISPENSING ATTACHMENT FOR CONTAINERS

Orman H. Maud, Albany, N. Y.

Application January 26, 1949, Serial No. 72,834

3 Claims. (Cl. 209—389)

1

The present invention relates to a device which takes the form of an attachment for the threaded discharge neck of a container such as is used on a restaurant table for dispensing limited charges of sugar in accordance with the discretion of each individual user.

It is a matter of common knowledge to those familiar with the construction and use of such sugar dispensing containers that the sugar often gets lumpy and the lumps lodge in the spill-type cap and interrupt the free flow of sugar. The object of the present invention is, therefore, to provide a sugar sifting and de-lumping screen which intercepts the sugar as it is shaken out of the container, said screen being provided with a scraper which breaks up the lumps, clears the screen of sugar dislodgements and keeps the screen sufficiently clean to insure uninterrupted dispensing accomplishments.

Another object of the invention is to provide a structural assemblage as broadly defined wherein, more specifically, the rotary scraper is centrally pivoted to the screen means and is adapted to be switched back and forth in wiping contact with the screen in a manner to thus loosen and dislodge sugar accumulations and clear the screen sufficiently that it will effectively allow sugar to filter therethrough without impediment.

In order to realize other objectives within the purview of the instant invention, I utilize a circular scraper equipped screen and assemble same within the confines of a screw cap which attaches to the sugar container and in addition provide a split ring-like spring which is removably snapped into the cap ring in order to provide a simple and practical assemblage of main parts which, collectively, provide an efficient screened closure for said container.

Other objects and advantages will become more readily apparent from the following description and the accompanying illustrative drawings.

In the drawings, wherein like numerals are employed to designate like parts throughout the views:

Figure 1 is a view in section which shows the complete attachment for the jar or container, said attachment forming a partial closure for the neck or mouth portion of the container;

Figure 2 is a top plan view based on Figure 1;

Figure 3 is an enlarged fragmentary detail section on the line 3—3 of Figure 2, looking in the direction of the arrows;

Figure 4 is a similar fragmentary sectional view on the line 4—4 of Figure 2.

Figure 5 is a perspective view of the flanged rotary scraper;

2

Figure 6 is a perspective view of the screen assembling and retaining member.

In the drawings in Figure 1, the sugar container, which may be a jar or the like, is denoted by the numeral 8 and has the usual open upper end which is screw-threaded at 9 and which may be referred to as the mouth of the container. The capping ring, sometimes referred to as a screw cap, is denoted by the numeral 10 and comprises a screw-threaded ring portion 11 which screws onto the threads 9 and an inturned annular capping flange 12 which is of sufficient cross-section to assemble and retain the parts which coact therewith.

15 As stated, the sugar intercepting, distributing and sifting screen, which is here shown constructed of interconnected wires crossing one another, is circular and is denoted in the drawings by the numeral 13. The intersecting wires as brought out, for example, in Figure 4 are distinguished by the numerals 14 and 15. The end portions of the wires are connected with an assembling and retaining annulus or rim member 16. The latter is provided on one side with a

20 struck out tongue 17 having a laterally bent retentive terminal 18. On the diametrically opposite side is a similar tongue 19 struck out from the notch 20 and having a lateral retentive terminal or detent 21 (see Figure 3). The numeral 22 designates a wide strap-like element which

25 may be conveniently described as a spider and this rests on and extends across the central top side of the screen and has its opposite ends bent to form hooks 23 which are engaged beneath the rim member 16 of the screen in the manner shown. This spider is essentially a foundation or mount for the rotary screen clearing scraper unit 24. This unit 24 is channel-shaped in cross-section and the web or bight portion is denoted at 25 and the flanges at 26 and 27, said flanges serving as convenient upstanding finger-grips. The scraper proper is the bight portion 25 and this has wiping contact with the screen and it also serves to accommodate an

30 attaching and assembling staple. The staple is denoted in Figure 1 by the numeral 28 and the prong portions 29 and 30 extend through an aperture in the central part of the web 25 and said prongs are bent apart so that a cotter key connection is thus had. The connection is such that the scraper is not only attached to the spider but the scraper rotates freely in relation to the spider and screen wire. In addition to the screen, I find it advisable to provide a wear element and this takes the form of an annulus or ring 31 which is of a diameter corresponding

35 to the outer diameter of the screen. The ring 31 is secured to the spider 22 by means of a suitable adhesive or cement.

to the rim member 16 of the screen and which is superposed in relation to said rim as brought out in Figures 3 and 4. The wear ring 31 has an arcuate slot on one side as at 32 in Figure 2. On the diametrically opposite side there is a bayonet slot, the entrance or notch portion of which is indicated at 33 and the restricted lateral end portion at 34. From this arrangement it will be seen that the ring 31 is placed atop the rim portion of the screen and the tongue 17 is passed through the slot 32 and the lateral portion is bent as at 18 to provide an interlocking connection between the rim member 16 and ring 31. The tongue 19 on the opposite side is fed in through the entrance notch 33 and by rotating the ring 31 a slight turn in relation to the rim member 16 the tongue 19 feeds into the keeper restriction 34 and the free end of the tongue is bent at 21 to thus assemble the parts. Additional slots 35 and 36 are provided and these have their edge portions bent in in parallelism and to provide spacing elements which slightly space the ring 31 from the rim of the screen. The thus attached ring 31 serves as 20 portions of a trackway or runner and the outer end portions of the rotary scraper ride in contact therewith to prevent undue wear on the screen wires. The assembling of parts is such, however, that the portion 25 of the scraper is sufficiently close to the screen that it is said to have sweeping or "wiping" contact with the screen. The wear ring 31 is not perhaps essential and in most of the subjoined claims is omitted as an unnecessary limitation since the primary arrangement is to have a circular or disk-like screen with a 25 rotary scraper to be fitted within the confines of the capping ring 10 so that the screen may be thus removably mounted on the mouth portion of the sugar jar.

Reference being had additionally to Figure 1, it will be seen that the ring 11 has, just below the flange 12, an endless indentation 37 providing a retaining seat for a split resilient ring 38 which constitutes a screen assembling and retaining spring. This spring is "snapped" into the channel or seat outwardly of the lip of the 45 container as shown in Figure 1 and comes into proper mechanical association with the screen that the latter is removably held within the confines of said capping ring 10. The flange 12 on the ring overhangs the annulus 31 and thus we 50 visualize the assemblage made up of the circular screen, wear annulus 31 fastened around the margin of the screen, and the pivotally attached scraper (three complementary parts) held as an assemblage in the surrounding cap ring 10 and pressing against the underside of flange 12 and held against said flange 12 by way of the split ring 38.

I am concerned with the idea of providing a suitable screen to partially close the mouth of a glass or equivalent sugar containing and dispensing jar which is preferably held in place by a cap ring of the type indicated at 10 and which is provided with a suitable rotary scraper 24 which is turned by hand and which scraper serves to break up sugar lumps and accumulations and to sufficiently reduce same that the resultant particles will be free of adherence to the screen and will keep the screen sufficiently clear that clogging will be reduced to a minimum. Hence, by providing a substantially clog-proof screen the sugar passing therethrough is repeatedly conditioned for effective dispensing use.

Changes in shape, size, materials and rear- 75

rangements of details and parts may be resorted to in actual practice, so long as they do not depart from the spirit of the invention or the scope of the appended claims, as is well understood.

Having described the invention, what is claimed as new is:

1. In a sugar container attachment of the class described, a flat circular screen, an annular wear member superposed upon the outer peripheral surface portion of said screen, said screen having a marginal reinforcing rim and said wear member being in parallelism above said rim, said rim having retaining and assembling tongues and said annular member having apertures for releasable reception of said tongues, a scraper comprising a channel-shaped member pivotally connected intermediate its ends to the central portion of said screen, the outer ends of said scraper being in rotary contact with said wear member.

2. A sifting and de-lumping attachment for the discharge end of a sugar container such as is used on table-type sugar dispensers comprising a circular sifting screen, an annular rim member underlying said screen and coacting with the marginal portion of the latter, a spider centrally spanning the top surface of said screen and having opposite end portions bent over the margins of the screen and underlying said rim, an annulus resting atop said screen and having diametrically opposite portions resting atop the coacting ends of said spider and coinciding with the marginal edge of the screen and underlying rim, means joining the rim and annulus together, and a screen scraper, said scraper being channel-shaped in cross-section and embodying a flat bight portion centrally and pivotally connected to the axial central portion of said spider and further having upstanding spaced parallel flanges, said flanges providing finger-grips and being adapted to be grasped for purposes of rotating the scraper in relation to said spider and screen, the end portions of said scraper overlying said annulus.

3. The structure specified in claim 2 and a capping ring provided with screw threads and also having an inturned capping flange, said capping flange overlying said annulus, said capping ring being provided with an indentation forming a keeper-channel, and a split resilient ring threaded removably in said channel and engaging said rim and serving to assemble and retain the rim, screen and annulus between itself and said inturned flange.
